DISPLAY FOR AN ELECTRONIC GAMING MACHINE" and filed on Dec. 4, 2018, and to U.S. patent application Ser. No. 29/672,329, entitled "CURVED BUTTON PANEL DISPLAY FOR AN ELECTRONIC GAMING MACHINE" and filed on Dec. 4, 2018, all of which are hereby incorporated by reference and for all purposes.

FIG. 1 is an isometric view of a curved button panel display for an electronic gaming machine, the curved button panel display having a tri-lobe button.

FIG. 2 is a top view of the curved button panel display for an electronic gaming machine of FIG. 1.

FIG. 3 is a front view of the curved button panel display for an electronic gaming machine of FIG. 1.

FIG. 4 is a left-side view of the curved button panel display for an electronic gaming machine of FIG. 1.

FIG. 5 is a right-side view of the curved button panel display for an electronic gaming machine of FIG. 1.

FIG. 6 is a back view of the curved button panel display for an electronic gaming machine of FIG. 1; and,

FIG. 7 is a bottom view of the curved button panel display for an electronic gaming machine of FIG. 1.

A curved button panel display for an electronic gaming machine is shown in FIGS. 1-7. The curved button panel display depicted in FIGS. 1-7. Broken lines, e.g., dashed or dotted lines, are used to depict features or elements that are not considered to be part of the claimed design.
